UNITED STATES PATENT OFFICE.

FRANK CHALFANT, OF FORT WAYNE, INDIANA.

MILK-CAN.

1,298,884.

Specification of Letters Patent.

Patented Apr. 1, 1919.

Application filed August 18, 1916. Serial No. 115,641.

To all whom it may concern:

Be it known that I, FRANK CHALFANT, a citizen of the United States, residing at Fort Wayne, in the county of Allen and State of Indiana, have invented new and useful Improvements in Milk-Cans, of which the following is a specification.

The invention relates to milk cans, and particularly to cans in which milk is shipped from one point to another. The well known and commonly used milk can is provided with a contracted top terminating in a neck into which the cover fits and the handles are usually secured to the sloping top. The cover is usually provided with a handle on its upper surface. It is a very difficult matter to thoroughly clean this type of can because of the constricted top and neck. The sun cannot reach all parts of the interior of the open can and in the absence of an appliance for the purpose the can is cleaned by hand with great difficulty. It is also impossible or unsafe to stack the cans one upon another since the top is smaller than the bottom.

The objects of my invention are to provide a milk can which may be easily and thoroughly cleaned, and is therefore sanitary, and which may be safely placed upon another in shipping so as to require less room in a car for a given number of cans than heretofore. Another object is to provide a can in which the tendency to burst open by the gas from sour milk within it is reduced to a minimum.

The invention consists in the provision of a can of uniform internal diameter throughout its length and equipping it with a flat cover which may be securely and resiliently fastened thereto.

In the accompanying drawings I have illustrated one manner in which the invention may be carried out in practice, in which

Figure 1 is an elevational view, partly in section, of the can constructed according to my invention.

Fig. 2 is an elevational view of the same taken at right angles to the view of Fig. 1.

Fig. 3 is a plan view of the can, the cover being removed.

Fig. 4 is an elevational view, partly in section, of the latch and handle supporting device.

Fig. 5 is an elevational view of the latch lever.

Fig. 6 is a plan view of the cover.

Fig. 7 is an elevational view of the cover.

In the illustration of the invention shown in the drawings, 10 is the can body, the internal diameter of which is uniform from its mouth to its bottom. The bottom 11 is curved so that there shall be no crevices or angular portions between it and the wall of the can body. A depending flange 12 is, if desirable, secured to the wall of the can, which serves to support the can in upright position and also protects the bottom from injury. The rim of the can body is turned over upon itself to form a seat 13 for the cover 14, or the seat may be provided by securing a band of metal about the rim of the can.

The cover 14 is flat at its top and is provided with a shoulder 15 and depending flange 16, the flange being adapted to be inserted in the mouth of the can with shoulder 15 engaged on seat 13. If desirable a suitable gasket 16^a may be used between the shoulder and seat to render the joint fluid tight. Two apertured members or rings 17 project laterally from opposite sides of the cover and are adapted to be engaged by the locking latches 18.

Latches 18 are of any suitable form. Each latch is adapted, at one end 19, to engage member 17 and at its other end it is pivoted to a shaft 21 fixed within the bifurcated end 22 of lever 23. A suitable portion 20 of the latch is coiled or otherwise formed to produce a suitable spring which will be useful in assembling the cover and which will permit the cover to rise off its seat in case the milk in the can should ferment and gas accumulate in the can, it being a well known fact that many cans are bursted open by the gas given off by milk which has turned. By the use of my spring latches the cover will unseat under the pressure produced by the accumulated gas and permit the gas to escape and thereby prevent injury to the can.

Lever 23 is pivoted to ring 24 by pins 25 which are driven through apertures 26 provided in the ring, the ring being cut out at 27 to accommodate the bifurcated end of the lever. The ring may be integral with or attached to the can body. Shaft 21 is situated below the pivotal point of the lever and the lever is cut out in its central portion to provide a recess or opening 28 in which the latch will hang when not in use.

At suitable points in the ring are two cut out portions 29 each having an over-

hanging shelf 30, each end wall adjacent the shelf having a recess adapted to receive the bent end of handle 31. The handle is formed of suitable material which will permit its 5 ends to be sprung into the latter apertures and enable the handle to pivot in said end walls. When not in use the handles will depend and lie against or close to the wall of the can body, and to use them each is 10 swung upwardly until its arms meet the shelf 30 whereupon further upward movement of the handle is prevented and the can is easily lifted by the handles, and upon releasing the handles they fall down into 15 normal position.

Levers 23 normally lie against or close to the wall of the can body. When the latches are to be connected to the cover the levers are elevated on their pivots, the latches are 20 engaged in members 17 and the levers are then forced downwardly against the can body. Since the pivotal point of the lever is above and forward of the pivotal point of the latch, the latch is securely fixed to the cover when the lever is drawn down to its 25 lowermost position. At the same time the cover is drawn down tightly upon its seat, yet it is seated resiliently by the latches. Any suitable bearings on the can body will 30 suffice for supporting the levers and handles.

It is apparent that the wide mouth and straight inside walls of the can body afford thorough cleansing of the can, and the flat cover permits of the ready placing thereon 35 of another can.

It is also apparent that the can may be used for the transportation of many liquids, hence I contemplate adapting it for all uses to which it is applicable.

40 For the purpose of sealing the cover to the can body I provide two lugs 32, which are apertured, on opposite sides of the can body and adjacent levers 23, to each set of which the ordinary seal may be attached, the seal 45 passing over the top of the lever in its nor-

mal depending position. The seal must, therefore, be broken before the cover can be removed.

What I claim is:

1. The combination of a can body having 50 a seat at its mouth, a cover for the body having a flat top and adapted to engage the seat, an apertured member projecting laterally from the side of the cover, a lever pivotally mounted on the can body, and having 55 an opening therein extending from its pivotal point toward its opposite end and a latch pivotally connected to the lever forwardly of the pivotal point of the lever and adapted to be engaged in the apertured 60 member when the lever is moved upwardly and to be drawn downwardly by the lever when the latter is moved downwardly for seating the cover, the latch being also adapted to be moved downwardly into the 65 opening in the lever when disengaged from the apertured member.

2. The combination of a can body having a seat at its mouth, a cover for the body adapted to be engaged on the seat, an apertured member projecting laterally from the side of the cover, a ring secured to the exterior of the can body and below the said seat, a lever having one end bifurcated and pivotally connected to the ring and a latch pivotally connected to the lever forwardly of the pivotal point of the lever and adapted to be engaged in the apertured member when the lever is moved upwardly and to be drawn downwardly by the downward movement of 80 the lever for tightening the cover on the seat, the latch being also adapted to be moved within the bifurcated end of the lever when disengaged from the apertured member, and means to seal the lever in active 85 position.

In witness whereof I have hereunto affixed my name this 16th day of August, 1916.

FRANK CHALFANT.
